Inventor:

William Arthur Mitchell

UNITED STATES PATENT OFFICE.

WILLIAM ARTHUR MITCHELL, OF NEWBURGH, NEW YORK.

CHRISTMAS-TREE HOLDER.

No. 909,634.

Specification of Letters Patent.

Patented Jan. 12, 1909.

Application filed January 31, 1908. Serial No. 413,604.

To all whom it may concern:

Be it known that I, WILLIAM ARTHUR MITCHELL, a citizen of the United States, residing at Newburgh, in the county of 5 Orange and State of New York, have invented a new and useful Christmas-Tree Holder, of which the following is a specification.

My invention relates to means for supporting a Christmas tree in an upright position, and is designed to afford a device embodying absolute simplicity with cheapness of structure; which can be quickly and conveniently adjusted and applied to 10 any ordinary diameter of Christmas tree trunk; which will afford ample lateral support therefor on all sides; which will allow of the use of a tree having branches very low and close to the point of support; and 15 which can be readily taken apart and packed in compact form for storage or transportation.

The invention consists in the construction and arrangement of parts hereinafter described and claimed specifically.

In the accompanying drawings, Figure 1, is a top view of the entire holder; Fig. 2, a view of the under side of the holder; Fig. 3, an edge view; and Fig. 4, a section upon 30 plane of line 4—4, Fig. 1.

My device is "knock down" in character, in that the parts may be readily assembled for use, and as readily taken apart and packed in a comparatively small space.

It consists essentially of two clamping bars A, A, two cross braces B, B, (said clamping bars and cross braces being preferably of uniform length) two bolts C, C, and connections, and the screws G, all of 35 which, when taken apart, may obviously be packed together in parallel positions and in close contact, when not desired for use.

When assembled for use, a cross brace B, is fitted to each clamping bar A, being inserted in one of the recesses F, formed for 40 its reception in the clamping bar A, the two parts being secured together by a screw G, so as to constitute together a rectangular, L-shaped member. The two L-shaped members thus formed are laid together around

the tree trunk with the clamping bars parallel and the cross braces B of one clamping bar A, resting in a recess F of the opposed clamping bar. The screw bolts C, C, are then passed through coinciding holes formed 55 for their reception (see Fig. 4) in the clamping bars, and the washers E, E, and thumb nuts D, D, applied.

The opposed surfaces of the clamping bars A, are formed with coinciding vertical 60 concave bearing surfaces H, H, for contact with the tree trunk. These concave bearing surfaces, H, H, hug the convex surface of the tree trunk and prevent any slip or inclination thereof when the clamping bars A, are 65 firmly secured to the trunk by means of the thumb nuts D.

By my arrangements of parts a broad and uniform area of lateral floor support is attained on all sides of the tree trunk; and as 70 the height of the device is that of the clamping bars A, which is but slight, say $2\frac{1}{2}$ inches, it is obvious that a tree trunk having 75 very low branches may be used, thereby economizing space and affording a more attractive appearance. The brace rods not only afford floor support but also by sliding in the opposed clamping bars preserve the 80 alinement and relation of the parts, while permitting the adjustment of the clamping bars with relation to each other and to the tree.

The rectangular members formed each by the securing together of a clamping bar A, and a cross brace B, each rectangular member being slidable upon and with relation to the other in such manner as to preserve the alinement of the parts and the parallelism of the clamping bars A, A, constitute a distinguishing feature of my invention, and 85 enable me to produce a cheap device of great simplicity, which may be readily assembled and applied for use, or taken apart and stored in compact form without the aid of skilled labor or the use of extraneous 90 tools or appliances.

What I claim as my invention and desire to secure by Letters Patent is,

In a device of the character designated, 100 the combination of two members each con-

sisting of a clamping bar, and a cross brace, said clamping bar being provided with a concave bearing surface and secured to the cross brace at right angles thereto, the cross brace of one member being slidable in a recess formed for its reception in the clamping bar of the other member, and a series of

bolts connecting the opposed clamping bars as and for the purpose specified.

WILLIAM ARTHUR MITCHELL.
